UNITED STATES PATENT OFFICE.

GEORGE W. SPOTSWOOD, OF MOBILE, ALABAMA.

SUSPENDERS.

No. 874,257.

Specification of Letters Patent.

Patented Dec. 17, 1907.

Application filed June 24, 1904. Serial No. 214,020.

To all whom it may concern:

Be it known that I, GEORGE W. SPOTSWOOD, a citizen of the United States, residing at Mobile, in the county of Mobile and State 5 of Alabama, have invented new and useful Improvements in Suspenders, of which the following is a specification.

This invention relates to suspenders for trousers or other articles of wearing apparel, 10 and one of the objects thereof is to provide, in a manner as hereinafter set forth, a form of suspender which when worn is adapted to insure comfort to the wearer, to overcome any leverage upon the shoulders, and to 15 bring the chief point of resistance directly at or near the top of the spinal column, which is the point where the greatest weight can be sustained with minimum exertion and fatigue.

20 A further object of the invention is to provide a suspender, in a manner as hereinafter set forth, which will embody in its construction but two terminals for attachment to the article of wearing apparel which is to be supported, the suspender being so constructed 25 that when used it does not tire or tax the muscles, it relieves the shoulders, chest, stomach, spine and back from pressure and restraint, allowing a free unobstructed respiration and 30 does not traverse any region where the nerves of the body are unprotected and is adapted to rest largely upon a portion of the frame of the body.

35 A further object of the invention is to provide a suspender embodying a centrally-disposed horizontal portion which acts to sustain the trousers or other wearing apparel when a person is in an upright position or when sitting or lying down, the horizontally- 40 extending portion being so shaped that it relieves tension on the body, consequently giving ease and rest to the wearer of the suspender, overcoming all strain and inconvenience which is invariably caused by the class 45 of suspenders now in general use.

50 A further object of the invention is to provide a suspender, in a manner as hereinafter set forth, which will hold the garment easily, naturally, evenly and in perfect accord with the design of the tailor.

55 Further objects of the invention are to construct a suspender, in a manner as hereinafter set forth, which shall be simple in its construction, strong, durable, efficient in its use, and comparatively inexpensive to manufacture.

With the foregoing and other objects in view, the invention consists in the novel construction of suspender hereinafter more specifically described, illustrated in the accompanying drawings and particularly pointed out in the claim hereunto appended. 60

In describing the invention in detail reference is had to the accompanying drawings forming a part of this application, wherein 65 like reference characters denote corresponding parts throughout the several views, and in which—

Figure 1 is a plan view of a suspender constructed in accordance with this invention, 70 and, Fig. 2 shows the appearance of the suspender when in use.

A suspender in accordance with this invention is formed from a strip of suitable flexible material substantially arch-shaped 75 in contour and embodies a centrally-disposed and horizontally-extending portion 1, which terminates at each end in a divergent portion 2 of compound curvature. Each of the portions 2 is formed with a terminal portion 80 3. To each of the terminal portions 3 is attached any suitable means for connecting the ends of the strips to a garment. The portions 3 diverge with respect to each other.

When the strip is used or adjusted to a person, the position of the same is as follows: 85 The center of the portion 1 rests below the point usually occupied by a collar button when inserted in the neck-band of a shirt. The portion 1 extends downwardly or backwardly to and over the first dorsal vertebra, or the first bone of the dorsal column; or in other words, occupies the region over or between the seventh and last bone of the neck 90 and the first bone of the dorsal column. The portion 1 extends in a horizontal manner towards either side of the neck, then curves 95 downwardly and follows the natural curvature formed by the junction of the muscles of the lower neck, shoulder and breast to about opposite the middle of the anterior 100 point of the shoulder. The strip then curves downwardly somewhat obliquely to an extent of about one-half to one inch of the beginning of the arm-pit, continuing thence at 105 the same angle until it reaches and intersects the waist-band at a point occupying a position under the center of the arm-pit so as to rest directly over the hip joint.

110 It will of course be evident that at times it will be necessary to increase or modify the degree of curvature or angles as necessity

may require so as to suit the portions of the human form.

What I claim is—

A garment suspender comprising an arch-shaped strip of flexible material embodying in its construction a pair of outwardly-projecting diverging terminal portions, said terminal portions providing the sole points of connection between the strip and the garment, said strip further comprising a pair of diverging portions of compound curvature terminating in said terminal portions, and

said strip further formed with a horizontally-extending centrally disposed portion which terminates in said diverging portions of compound curvature. 15

In testimony whereof I have hereunto set my hand in presence of two subscribing witnesses.

GEORGE W. SPOTSWOOD.
